PACKAGE FOR STRIP LABELS

Thomas Riley, South Norwalk, Conn., assignor
to J & J Cash, Incorporated, South Norwalk,
Conn., a corporation of Connecticut

Application January 27, 1939, Serial No. 253,184

5 Claims. (Cl. 206—51)

This invention relates to packaging device and more particularly to a device for packaging name strip labels commonly used for identifying garments.

5 These name labels are ordinarily manufactured in strips slightly over a foot in length and each comprising a plurality of individual name labels which can be cut off as desired and applied to garments.

10 The object of the present invention is to provide an improved and simplified device in which a plurality of such strips can be efficiently packed for shipment and in which they can be retained and preserved without soiling by the user and 15 can be readily identified as to the content of the package without opening the same.

Other objects and advantages will more fully appear in the course of the following detailed description.

20 The invention consists in the novel construction, arrangement, and combinations of parts hereinafter more particularly described and claimed.

One sheet of drawings accompanies this specification as part thereof in which like reference characters indicate like parts throughout.

Figure 1 is a plan view of the assembled device;

Figure 2 is a perspective view of the assembled device except for the outer envelope;

30 Figure 3 is a transverse cross sectional view taken on line 3—3 of Figure 1;

Figure 4 is a longitudinal cross sectional view taken on line 4—4 of Figure 1;

Figure 5 is a perspective view of one of the end 35 closures; and

Figure 6 is a plan view of the supporting card unfolded.

Figure 7 is a plan view of a part of a holding card showing a modified construction of prong 40 members.

Figure 8 is a transverse cross sectional view taken on line 8—8 of Fig. 7.

Referring to the drawing: The improved package comprises a strip holding card 1 associated 45 with two end closure envelopes 9 and an all-enclosing envelope 10. These three major elements will be described separately in order.

The supporting card 1 is preferably formed from cardboard or the like and is rectangular in 50 shape and of a length substantially twice that of the all-enclosing envelope 10. The card 1 is provided with a plurality of struck-up prong members 2 arranged longitudinally of the card in spaced parallel lines. The card 1 is provided 55 with transverse fold lines 3—3 each spaced one-

quarter of the length of the entire card from the respective ends thereof and on these fold lines 3—3 are provided a plurality of cut-out windows 4, said windows being spaced and arranged in alignment with the respective lines of prong members 2, so that when the card 1 is folded upon itself on the lines 3—3 the cut-out windows 4 provide notches at each end of the folded card in alignment with the respective lines of the prong members. Preferably the prongs 2 are 10 arranged in each line in pairs of two, their being in each line two prongs upon each end portion of the card and two prongs in the middle portion of the card, and these pairs of prongs are preferably spaced apart a distance slightly greater than the length of an individual name label. In 15 this manner a plurality of name label strips, each substantially the length of the supporting card 1, can be arranged in groups, each group being positioned under the prongs of a line of prongs and when the card is folded upon itself the folds of each group of strip labels will be secured in the notches formed by windows 4 as illustrated.

End closures 9 for the folded card are provided, each of which consists of an envelope having a 20 closed end 13 and a projecting back or lip 14, extending beyond the mouth of the envelope. The length of each envelope with its projecting lip is substantially one-half the length of the folded card so that when the card is folded with the assembled strip labels and the end closures are applied, as illustrated in Figure 2 the lips 14 will 25 abut on the back of the folded card while the faces of the envelopes will be spaced apart on the face of the card substantially the length 30 of an individual label. The all-enclosing envelope 10 is provided with a transparent window 11 positioned in such a manner that when the folded card 1 secured by the end closure envelopes 9 is positioned in envelope 10 one of the 35 name labels will be disposed behind the transparent window 11.

In the modified form of invention illustrated in Figs. 7 and 8, the prong members 2 are each provided with a much smaller oppositely disposed 45 struck-out prong member 15 so that the label strips can be secured between prong members 2 and 15 and thus secured against withdrawal except in a longitudinal direction.

Where the particular consignment of name 50 labels are to be delivered to the same person whose name has been woven into the strip labels it will be apparent that it will only be necessary to type upon the face of the all-enclosing envelope 10 the party's post office address and after 55

receipt the package can be retained and will readily disclose at all times the nature of the contents thereof by reason of the label appearing behind the window.

- 5 5 Various modifications will readily suggest themselves to those skilled in the art but within the scope of the present invention as claimed.

Having fully described my invention I claim:

1. A holder for name strip labels comprising a 10 card having prongs struck therefrom under which the labels can be positioned, said prongs arranged in a horizontal row and two of the prongs spaced apart the length of a name on a label, with slip end covers in the form of envelopes 15 each having a back extending beyond its mouth adapted to removably embrace the card and assembled strip labels at each end whereby the part of the label between said specified prongs will be exposed when the extended backs of the 20 envelopes abut over the card and labels.

2. The structure of claim 1 in which the card is provided with transverse folds defining end parts each one-half the length of the central part and in which the prongs are arranged in a plurality of horizontal rows, with at least two prongs of each row on the middle and each end part of the card and the card provided with polygonal cut-out windows two for each horizontal 25 row of prongs and positioned at the lines of fold in said card.

3. A holder for name strip labels comprising a card having prongs struck therefrom under which the labels can be positioned, said prongs arranged in a horizontal row and two of the 30 prongs spaced apart the length of a name on a

label, with slip end covers in the form of envelopes adapted to embrace the card and assembled strip labels at each end each envelope having a back extending beyond the mouth thereof in which the card is provided with transverse folds 5 defining end parts each one-half the length of the central part and in which the prongs are arranged in a plurality of horizontal rows, with at least two prongs of each row on the middle and each end part of the card and the card provided 10 with polygonal cut out windows two for each horizontal row of prongs and positioned at the lines of fold in said card with a sheet of transparent material such as Cellophane and an envelope provided with a window, each of substantially the size of the intermediate part of the card.

4. A holder for name strip labels comprising a rectangular card having transverse lines of fold defining end parts each one-half of the length of 20 the intermediate part and having prongs struck therefrom in a line extending lengthwise of the card at least one prong of said line of prongs in each end part and at least two of said prongs in the intermediate part and said card having windows cut out over each line of fold in alignment 25 with the line of prongs.

5. A holder for name strip labels comprising a card having prongs struck therefrom under which the labels can be positioned, said prongs 30 arranged in a horizontal row and each prong having a smaller prong struck therefrom, the free ends of each main and subordinate prong oppositely disposed.

THOMAS RILEY. 35
